UNITED STATES PATENT OFFICE.

HENRY T. PAISTE, OF PHILADELPHIA, PENNSYLVANIA.

ATTACHMENT-PLUG.

965,733.

Specification of Letters Patent. Patented July 26, 1910.

Application filed September 20, 1907. Serial No. 393,784.

To all whom it may concern:

Be it known that I, HENRY T. PAISTE, a citizen of the United States, residing in Philadelphia, Pennsylvania, have invented 5 certain Improvements in Attachment-Plugs, of which the following is a specification.

One object of my invention is to provide an attachment plug of relatively simple and compact construction which shall have its 10 parts so arranged that one section of the plug is free to swivel on the other without injury to the parts or danger of short circuiting any of the connections.

It is further desired to provide an attachment plug having two separable parts provided with means for detachably holding them together, so designed as to permit of their connection by a straight line movement of one part toward the other.

20 These objects and other advantageous ends I attain as hereinafter set forth, reference being had to the accompanying drawings, in which:

Figure 1, is a vertical section of one part 25 of my improved attachment plug; Fig. 2, is a vertical section of the other part of the plug; Fig. 3, is a vertical section of that part of the plug illustrated in Fig. 2, the same being taken on the line 3—3, of said 30 figure, and Fig. 4, is a horizontal section taken on the line 4—4, Fig. 1.

Referring first to Figs. 1 and 4, the section therein illustrated is that designed for the connection of a flexible cord or double 35 conductor cable, and consists of a body A of porcelain or other suitable non-conducting material having a metallic cap or cover a. This latter has a lining a' of fiber or mica and is provided with an outlet in which are 40 placed two insulating bushings a² and a³. On that face of the body A within the cap a is mounted a curved metallic plate b and this is placed in a similarly curved recess so as to be mechanically separated by a wall a⁴ of insulating material from the second metallic 45 piece or terminal c which is placed in a second recess in the same face of the body. The piece b is provided with a terminal screw b' for the attachment of a conductor and is held in place as well as electrically connected to a second metallic piece b², by means of a screw b³. This latter piece is sunk in a suitable recess in the outer face of the body A so as to be flush with or below the surface of 50 the same and extends from one side of said

face to and slightly beyond the center thereof.

Centrally located upon the outer face of the body A so as to project at right angles thereto, is a sleeve b⁴ which passes through an opening in the metallic plate b², and is flanged so as to be held to the body thereby as well as to insure its electrical connection to said plate. Within this sleeve there extends a metallic rod or plug c', insulated from it, however, by a sleeve d of fiber, mica or the like and threaded at its inner end so as to enter a suitably threaded opening in the terminal piece c above referred to. This terminal piece is provided with a terminal screw for the attachment of the second of the electrical conductors which may enter the cap a. The rod or plug c' is rounded at its outer end, and as shown, projects beyond the insulating sleeve d for a short distance. 75

The second member of the attachment plug consists of a disk E of porcelain or other suitable nonconducting material, to which is held a hollow cylinder E' also of porcelain, etc., by means of screws e countersunk in the outer face of the disk E and engaged by nuts e' placed in suitable recesses in the outer end of the part E', for holding the parts of the device together. There is an opening e² passing centrally through the 80 disk E and of a diameter but slightly larger than the diameter of the metallic sleeve b⁴. The two parts E and E' confine between their adjacent faces, the inwardly flanged end of a threaded metallic shell F, of the 85 well known Edison type, and it will be seen that where this inwardly flanged part approaches the opening e², it is provided with what are in effect spring tongue extensions f so shaped and arranged as to yieldingly, 90 but none the less certainly engage and electrically contact with the sleeve b⁴ when this is inserted in said opening.

Within the hollow of the cylindrical part E' and at the end thereof distant from the 100 opening e² is mounted a semicylindrical contact member g having a spring contact g' held to it by means of a screw g² which passes centrally through the end of the insulating body E' and serves to hold in place 105 a circular metal contact plate g³ as well as to electrically connect said plate to the spring contact members g and g'.

When the two members of the device are put together by entering the metallic plug c' 110

and the sleeve b^4 , in the opening e^2 , said plug engages and electrically connects with the contact members g and g' , which serve to hold the two members of the attachment 5 plug together by reason of their engagement with the rounded head c^3 of said plug. At the same time the sleeve b^4 is electrically engaged by the spring tongue f , so that it will be seen the two contact plates or members b 10 and c to which a pair of electrical conductors would be connected, are in turn electrically connected to the second pair of terminals of the plug formed by the threaded shell F and the metallic plate g^3 . In one case 15 the circuit would be completed from the terminal plate c through the plug c' to the contacts g and g' and through the screw g^2 to the plate g^3 , while in the other case the circuit would be completed from the terminal 20 plate b through the screw b^3 , plate b^2 , sleeve b^4 and tongue f to the threaded shell F .

I claim:—

1. The combination in an attachment plug of two members of which the first has two 5 terminals and two contacts connected thereto, one of the contacts being coaxial with the plug and the other being concentric therewith, while the second member consists of two bodies of insulating material, means 30 for holding said bodies together, two terminals including a metallic shell having an inwardly extending flange confined between the two bodies of insulating material by said holding means, with contacts respectively connected to said terminals and capable of engaging the contacts of the first 35 member.

2. The combination in an attachment plug of two members of which the first is provided with two terminals, a plug and a contact 40 respectively connected to said two terminals, the second member consisting of two bodies of insulating material, means for holding together said two bodies, a terminal shell having flanges confined between said 45 two parts of the second member and provided with a projecting tongue or tongues placed to engage the contact of the first member, and a terminal plate on the second 50 member having means electrically connected to it for engaging the plug of the first member.

3. The combination in an attachment plug of two members of which one has a plug, a metallic sleeve, and two terminals respectively connected to said plug and sleeve, and the second member consisting of a hollow cylinder having a central opening, a disk of insulating material, a threaded shell having a flange confined between said cylinder and the disk, means for holding together the cylinder and disk, a spring contact within the cylinder, a metallic plate on the outer face of the cylinder electrically connected to said spring contact, with 55 tongues on the flange of the threaded shell placed to electrically engage the sleeve of the first member when the plug thereon is forced into engagement with the spring contact. 60

4. A separable attachment plug comprising an insulating cap, electrically connected brackets secured thereto, one of which carries a stem having an insulating bushing fitting and secured to it, the other bracket 75 carrying a contact sleeve surrounding the insulating bushing, and an insulating base having a recess which receives the stem, bushing and contact sleeve and is provided with a contact ring which is engaged by the 80 contact sleeve and contact springs which are engaged by the stem. 70

5. A separable attachment plug comprising an insulating cap, electrically connected brackets secured thereto, one of which carries a stem, an insulating bushing fitting and secured to said stem, the other bracket carrying a contact sleeve surrounding the bushing, and an insulating base having a recess which receives the parts carried by 85 the cap and is provided with a center contact, contact springs which are engaged by the stem and are electrically connected with the center contact, a screw shell, and a contact ring which receives the contact sleeve 90 and is electrically connected with the screw shell. 95

In testimony whereof, I have signed my name to this specification, in the presence of two subscribing witnesses.

HENRY T. PAISTE.
